UNITED STATES PATENT OFFICE.

ALFRED SAVAGE, OF SALEM, OREGON.

CORD GRASPER AND CUTTER FOR GRAIN-BINDERS.

SPECIFICATION forming part of Letters Patent No. 274,828, dated March 27, 1883.

Application filed June 22, 1882. (No model.)

To all whom it may concern:

Be it known that I, ALFRED SAVAGE, of Salem, in the county of Marion and State of Oregon, have invented a new and Improved 5 Cord Holder and Cutter for Grain-Binders; and I do hereby declare that the following is a full, clear, and exact description of the same, reference being had to the accompanying drawings, forming part of this specification, in 10 which—

Figure 1 is a plan view of my improved cord grasper for grain-binders. Fig. 2 is a side view. Fig. 3 is a longitudinal section, and Fig. 4 is a cross-section of the same on line $\alpha\alpha$ of Fig. 1.

This invention relates to improvements in cord graspers and cutters for grain-binders, and has reference to that class of cord graspers and cutters which have for their object to 20 effect the grasping and holding the tying-cord of the binder previous to the severing thereof, which takes place after the binding of the bundle of grain, to prevent "losing" the end of the binding-cord; secondly, to enable the 25 ready adjustment of the cutter to accommodate the cutting of cords of different thicknesses; and, thirdly, to cause the grasper to act with a variable or yielding pressure upon the cord, and to relieve the roller of the grasper from undue strain or pressure.

The nature of my invention consists in the employment, in connection with a sleeve having a shoulder on its inner side, near the outer end, a sliding jaw having at its outer end a 35 hook or beak with a notched or toothed face, and an adjustable cutter or knife arranged at one side of the sleeve, of a jaw or palm cushioned upon springs seated upon brackets of the sleeve, and having also a notched or toothed 40 face, said face being arranged inward from and adapted to co-operate with the notched or toothed face of the hook of the sliding jaw, said palm or jaw having a shoulder or stop near its said end, substantially as hereinafter 45 more fully set forth.

In carrying out my invention I employ a sleeve, A, which is bolted or otherwise fastened to the binder-frame through an aperture, a, in its rear end.

50 B B' are the jaws which constitute the

grasper, and which are arranged within the sleeve A. The jaw or "palm" B has its outer end provided with notches or teeth b, as has also the beak of the hooked end of the jaw B', the purpose of which is to grasp and hold the 55 binding-cord. The jaw or palm B is capable of having an inwardly-yielding movement, as will be presently readily understood, to vary the pressure or relieve excessive strain on the binder by its action, with that of the jaw B', in 60 grasping and holding the cord. It is provided with a lateral shoulder, c, near its outer end, which is arranged a short distance outward from a shoulder, c', formed on the sleeve by reducing or shortening one side of the latter. 65 When brought into contact these two shoulders limit the inward movement of the palm or jaw B. Said jaw B is cushioned upon a 70 spring or springs, d, which receive studs or projections d' on a cross-bar, d'', preferably cast with its shank, and studs or projections e on the brackets e', bolted or otherwise fastened to the inner end of the sleeve A. These 75 springs permit the withdrawal of the palm or jaw B simultaneously with the inward movement of its fellow jaw, B', to take hold of the binding-cord, but press outwardly with sufficient force to enable it to unite with said jaw B' to properly grasp and hold the cord. It 80 will also be noticed that by the action of these 85 springs the palm or jaw B will, the instant the jaw is allowed to move outward, spring outward also, and follow up the jaw B', and thus continue to hold the cord, though severed from that passing around the bundle. The 90 severing operation is performed by the grasper, during its inward movement, carrying the cord against the knife or cutter C, arranged at the side of the sleeve. This movement of the grasper is caused by mechanism used in connection with a grain-binder to which I intend to apply my invention.

The knife is rendered adjustable by means of screws f' f'', passed through slots f f' in said knife and into screw-threaded apertures in the 95 sleeve A. The adjustability of the knife or cutter permits it to be accommodated to binding-cords of different thicknesses.

h is a guard on the outside of the knife or cutter.

Having thus described my invention, what I claim as new is—

The cord grasper and cutter for grain-binders, consisting of the sleeve A, having a shoulder, c' , formed thereon by reducing or shortening one of its sides, the adjustable cutter or knife C, affixed to one side thereof, the sliding jaw B', having at its outer end the beak or hook with a notched or toothed face, and the jaw or

palm B, cushioned upon springs, or a spring, 10 d , seated upon brackets of the sleeve A, and having near its outer end a shoulder, c , and a notched or toothed face, b , as and for the purpose set forth.

ALFRED SAVAGE.
